FINISHING STEREOTYPE PLATES

Nils Olsen Temte, Chicago, Ill., assignor to The
Goss Printing Press Company, Chicago, Ill., a
corporation of Illinois

Application June 1, 1940, Serial No. 338,334

11 Claims. (Cl. 90—26)

The invention relates to new and useful improvements in stereotype printing plate finishing mechanisms, and more particularly to such improvements in machines for finishing and matching companion stereotype plates for double-page printing, that is side-by-side plates carrying a unitary design.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation of a machine embodying the invention;

Fig. 2 is an end elevation of said machine viewed from the right of Fig. 1;

Fig. 3 is an enlarged, central vertical section of the upper part of said machine;

Fig. 4 is a vertical transverse section on line 4—4 of Fig. 3;

Fig. 5 is a view similar to Fig. 4, showing the plate clamping means in locked position;

Fig. 6 is a section on line 6—6 of Fig. 3;

Fig. 7 is an enlarged sectional detail showing the matching edge of two stereotype plates locked together in printing position on the plate cylinder of a printing press;

Fig. 8 is a wiring diagram of the motor and safety-guard interlock;

Fig. 9 is an end elevation of a clutch-operated modification of the machine;

Fig. 10 is an enlarged fragmentary section on line 10—10 of Fig. 9;

Fig. 11 is a section on line 11—11 of Fig. 10; and

Fig. 12 is a section on line 12—12 of Fig. 11.

It is sometimes required on rotary presses to print a unitary design which is two pages, that is, two plates in width, and in such cases it is necessary to clamp the arcuate abutting edges of both plates to the cylinder while at the same time the printing surfaces of the two plates must overlap these clamping edges and must abut on each other and be exactly matched and alined

so that the printing impression or unitary design made from the two plates will appear as though printed from a single plate. It is therefore necessary that the two arcuate abutting plate ends be finished exactly alike, both as to their printing surfaces and their clamp-engaging surfaces, so as to perfectly match and aline the two parts of the unitary design. Objects of the invention are to produce a plate-finishing machine, that is, a machine for finishing the two abutting arcuate plate edges to effect the results and requirements described; to provide means whereby the trimming and finishing of the second plate can be preliminarily determined or set from the corresponding edge of the first finished plate; to provide for finishing and matching in the manner described the tail ends of the two plates; to provide for removing the excess metal from the arcuate end of a plate in order that the plate can be effectively positioned in juxtaposition with a companion plate to effect the required alining and matching; and to effect the finishing of the plate, the alining and the matching in a minimum of time and in a manner convenient to the stereotyper.

To this end a machine is provided having a semi-cylindrical saddle for supporting a stereotype plate, the saddle being provided with supports for the straight edges of the plate to positively position the plate angularly and means engaging the arcuate cast end of the plate for positioning it axially on the saddle. Two sets of angularly-movable trimming knives are mounted near one end of the saddle, the two sets being a diameter apart, one set of knives effecting certain of the finishing cuts, the other set of knives effecting the remaining cuts to finish the plate end for cooperating with the clamping means and for matching with the companion plate. Manually operated means, including a differential screw feed, are provided for effecting exact and minute axial feed of the saddle and of the plate thereon relatively to the trimming knives. On the opposite side of the trimming knives is an auxiliary stationary saddle provided with supports for the straight edges of a companion plate previously finished, whereby the two plates are exactly alined angularly, but this companion plate is free for axial movement upon its saddle to and from the plate on the first-mentioned saddle for the purpose of matching the design at the two arcuate edges, the trimming knife carrier being positionable to permit this movement of the plate.

The invention also provides in its preferred

form a motorized drive for the trimming knives, and associated therewith a safety guard which is interlocked with the electrical circuits controlling the motor, whereby the guard must be in closed position during normal driving operation of the knives. Said motorized form of the invention is also provided with means for momentary or inching operation of the cutting mechanism and same is also interlocked with the operation of the safety guard.

It will be understood that the foregoing general description, and the following detail description as well, are exemplary and explanatory but are not restrictive of the invention.

Referring now in detail to the present preferred embodiment of the invention illustrated by way of example in the accompanying drawings, the mechanism shown in Figs. 1 to 7 is the preferred form embodying the electrical motor drive and safety guard interlock. As embodied a main frame 10 is designed to support a stationary cylindrical saddle 13, said saddle being adapted to hold a finished stereotype plate for matching with the other stereotype plate being trimmed on the machine. The saddle 13 is essentially a hollow cylinder rigidly supported at its lower periphery by spaced-apart arcuate stirrups 11 and 12 formed in the frame 10. The opposite or left hand portion of the frame 10 is designed to support a similar saddle 17, which, however, is adapted for axial movement to position the stereotype plate carried thereby with respect to the trimming tools. As shown, the cylindrical saddle 17 is supported from a central axially movable shaft 16, the ends of which are slidably mounted with respect to the main frame 10. For this purpose an upwardly-disposed arm 15 is provided at its upper end with a hub 15^a which is bored for sliding support of the end of the shaft 16. The opposite end of said shaft is slidably supported in a similar hub 14^a formed at the upper end of an upwardly inclined supporting arm 14. The cylindrical saddle 17 is rigidly connected to and supported by the shaft 16 by means of spaced apart hubs 18, 18 fixed to the shaft and having radially-extending spokes 19 formed integrally with the shell of the saddle 17.

To permit axial movement, the saddle 17 is substantially U-shaped in cross-section as will appear from Figs. 4 and 5. That is, the lower arcuate portion of the shell 17 is cut away along elements of the cylinder to provide clearance for axial movement with respect to the arms 14 and 15. The edges 21 of the saddle shell 17 are adapted to have sliding engagement with the sides of the upright 15, being provided with pads 22 which slide upon cooperating pads 23 on the members 15. In order to eliminate rocking of the saddle about the shaft 16 shims 24 may be employed between the pads or sliding surface 22 and 23. A cross-strut 25 bridging across the gap formed by the cut-away portion between the edges 21 is provided to prevent spreading of the saddle 17. Arcuate ribs 26 and 27 are also provided to give further internal rigidity to the shell.

Means are provided for clamping a stereotype plate 28 to the saddle 17 for the cutting operations and to seat same in a predetermined angular position. As will appear in Figs. 4 and 5 the plate 28 overlies substantially one-half the peripheral surface of the cylinder 17. The plate is ordinarily finished with a bevelled end 28^a, formed by a suitable tail cutter preliminarily to being placed on the saddle. Stop means for cooperating with said bevelled end 28^a for resisting

axial movement of the stereotype plate away from the cutter comprises an adjustable stop member 29 which embraces the upper part of the saddle 17 and is attached thereto by three cap screws 31 passing through slots 32 in the stop member 29 and threaded in the saddle.

Means for clamping the stereotype plate 28 to the saddle comprises longitudinal cleats 35 at either side of the saddle and diametrically disposed. The circumferential distance between said cleats is greater than that covered by a stereotype plate. In practice the operator lays the stereotype plate on the carrier 17, the edges of the plate ordinarily not resting against either cleat 35 as shown in Fig. 4 for example. However, the stops 35 assist in initially so positioning the plate on the saddle. The clamping or locking means comprises a leather band 36 attached to a metal band 37, said bands being designed to be wrapped and drawn tightly about the stereotype plate to the cylinder. For this purpose the right hand end of the bands is resiliently anchored to a bracket 39 on the saddle by a spring anchor connection 39^a while a pivoted locking handle 41 is attached to the opposite end of the band. Said handle is pivotally connected to locking brackets 44 on either side of the handle by means of pintles 42. Upon counter-clockwise rotation of the handle the pintles engage with lock niches 43 in the brackets 44 to hold the handle and strips in their closed or locking position. When the handle 41 is operated to clamp the plate to the saddle the ensuing rotation of strap 36, against the pull of the anchor spring 39^a, would cause the plate 28^a to slide around the saddle from the position of Fig. 4 to that of Fig. 5. In the latter position the left hand edge of the plate is then in a state of abutment against the left hand stop 35.

For removing the stereotype plate 28 from the saddle 17, a recess 45 is provided at the top of the saddle whereby a workman may place his hand under the plate and lift same from the machine when the locking band has been released.

In accordance with the invention, means are provided for cutting the desired edge surfaces on the end of the plate 28. The surfaces to be cut (Fig. 7) comprise the vertical edge A, the under-cut horizontal face B, the bevelled edge C and the vertical edge D. Cutting tools 100 are provided for cutting the surfaces A and D while other tools 101 are designed to cut the bevelled surface C and the horizontal face B. Said tools are mounted in a rotary carrier 105 which is keyed to turn with the motor driven shaft 52. The carrier comprises a pair of diametrically-opposed arms forming a single casting integral with a hub 106 keyed to the shaft 52. The cutting tool 100 is mounted in one arm of the carrier 105 while the tool 101 is mounted in the other arm 180 degrees apart.

One end of shaft 52 is journaled in the supporting hub 15^a which also receives the shaft 16, while the opposite end of shaft 52 is journaled in a hub 107 which forms the center of a spider or disc bridging the outer end of the saddle 13. At the inner end of saddle 13 there is formed a plurality of integral ribs 108 which terminate in a hub 109 in which the shaft 52 is intermediately journaled.

Rotation may be imparted to the tool carrier 105 for cutting the stereotype plate both by hand and by motor, it being rotated by hand for imparting the finishing touches in final matching operations, and also to position it for movement

of the matching plate 55. For this purpose the carrier 105 is provided at either extremity with handles 110. Motorized rotation is imparted by a motor driven belt 111 from a built-in motor 76 at the bottom of the machine, the lower end of the belt engaging the motor shaft sprocket 113 while the upper end passes over and drivingly engages a driving pulley 114, the hub of which is keyed to the shaft 52 and has thrust bearing against the hub 109. Thrust from the rotating tool 105 is taken up against a non-ferrous bearing ring 53 mounted on the inner end of the saddle 13 and a non-ferrous bushing 54 on the arm 15, so that substantially no endwise thrust is imparted to the shaft 52.

It will be understood that the carrier or saddle 17 is axially movable for the purpose of bringing the edge of the plate 28 into contact with the rotating cutting tools. The embodied means for imparting such to and fro movement to the carrier or saddle 17 comprises a head 43 bolted to the arm 14, and provided with a centrally-extending flange 47 which is held between a shoulder on an elongated nut 48 and a hub 49 of a hand wheel 51. The shaft 16 is connected to the nut 48 by a reversely threaded central member 50. Rotation of the hand wheel 51 will thereby be translated into axial motion of the saddle 17.

In operating the above described mechanism, an unfinished plate is fastened to the movable saddle 17, as above described, and is subjected to the cutting actions of the tools on the carrier 105. The finished plate 55 is then removed from saddle 17 and placed on the stationary saddle 13, along which it is slidable. It will be noted that the stationary saddle 13 is provided with a pair of axial cleats 35^a which are in accurate alignment with the cleats 35 on the saddle 17, so that the finished plate 55 will have its axial edges resting upon and supported by the cleats 35^a so that it will be in accurate angular alignment at all times with the plate 28. A second unfinished plate 28 is then fastened to the movable saddle 17 and the cutting operations applied to it. Between cutting operations the operator may slide the finished plate 55 toward and into abutment with the working plate 28 to see how the matching is progressing or whether his work has reached a state satisfactory for printing. It will be noted (Fig. 6) that the arms of the tool carrier can be swung into a horizontal position so that the finished plate 55 can be slid over the tools when such a test is desired.

In accordance with one feature of the invention there is provided a safety guard to protect the operator from the rotating tool carrier 105. The lower part 61 of said guard is rigidly fastened to the frame 10, while the upper part of lid 62 is hinged to the lower part at 63 on the rear side of the machine. When the lid 62 is in the closed position it rests at the front of the machine between a pair of cleats 64 extending upwardly from the part 61. Said cleats act as guides so that a cam 65 rigidly attached to the lid will effectively engage a limit switch 66.

Means are also provided for holding the lid closed, comprising a lever 67 pivoted at 68. The lever includes a jaw 69 adapted to hook beneath a pin 71 supported by lugs 72 extending from the lid 62. It will be noted that there is a lug 73 downwardly extending from the lid nearly to the surface of the saddle 13. The purpose of this is to prevent closing of the switch 66 by closing of the lid if the plate 55 has been inadvertently left

in insufficiently retracted position after a matching test. The lug 73 also precludes accidental movement of the plate 55 into engagement with the tool carrier when said carrier is rotating.

5 Chips from the stereotype plates find their way into the hollow base of the frame 10 from which they may be withdrawn by way of a door 75.

Referring now to that feature of the invention wherein operation of the safety guard is interlocked with that of the motor, the motor 76 is 10 operated from a three-wire circuit. In Fig. 8 it is assumed that the lid 62 is raised or thrown backward to its extreme position denoted by broken lines (Fig. 2). Closing of the lid causes closing 15 of the switch 66. To start the motor 76 the operator depresses a switch 77 (normally open by spring pressure) thus allowing current to flow from wire 78 to 79 by way of a solenoid 81; thereupon consequent energization of said solenoid causes closing of switches 82, 83, 84 and 85, thereby 20 starting the motor. Once the multiple switches 82-85 have been closed the motor will continue operation until pressure on switch 86 (normally closed by spring pressure) opens said 25 switch, whereupon the multiple switch is opened by gravity or spring pressure in known manner.

Provision is made for inching and this includes 30 a walking beam switch 89 which is not unlike an ordinary two-button wall switch for domestic lighting. It will be apparent that depressing the start switch 77 causes the motor to operate regardless of whether the switch 89 is open or closed. If the switch 89 is closed the motor will, of course, continue to run after pressure on the 35 button 77 has been removed. If, however, the switch 89 is open at the time switch 77 is depressed the motor will stop the moment pressure is removed from switch 77 since the latter is normally open. Therefore, it is by means of the 40 button 77 that inching is accomplished.

Resistances 91 and 92 included in the circuit 45 ordinarily do not provide enough heat to affect bimetal members 93 and 94, mechanically coupled respectively to switches 95 and 96, to open said switches. When, however, the load is above 50 100% of the intended load for the motor, heat generated by the resistances will cause the motor to stop due to opening of switches 95 and 96 since the heat produced by excessive load will warp the bimetals. The suddenness or slowness of stopping of the motor will be dependent, of course, on the amount of overload. Examples of the causes 55 of such overload would be when the work is fed too fast to the tools, or when some foreign body prevents rotation of the tool carrier, or when a stereotype plate extends improperly into the orbit of the tools to thereby prevent rotation of the tool carrier. The multiple switch, together with the overload thermostatic cutout device, are collectively known as a magnetic line starter and 60 any suitable form thereof may be employed with the matching machine of the present invention.

In Figs. 9 to 12, inclusive, is shown an alternative construction wherein the motor 76 is continuously operated and the tool carrier is coupled to the motor by means of a suitable friction clutch 201. A clutch shifting lever 202 extends through a slot 203 in the saddle and is retained in disengaged position by a latch 204 urged to 65 rotate clockwise about a stud 205 by a spring 206. When the operator desires to couple the motor to the tool carrier he depresses the latch, using a handle 207 to thereby move the latch out of the 70 path of movement of the lever 202 from the position shown to the broken line position.

The invention in its broader aspects is not limited to the specific mechanisms shown and described but departures may be made therefrom within the scope of the accompanying claims without departing from the principles of the invention and without sacrificing its chief advantages.

What I claim is:

1. A machine for finishing stereotype plates including in combination a saddle, means for supporting a plate thereon in trimming position, an angularly traveling cutter for trimming an arcuate end of said plate, an auxiliary plate supporting saddle adjacent said first saddle, and means for movably supporting a plate on said auxiliary saddle in axial and angular alinement with the plate in trimming position on said first-mentioned saddle whereby said second plate is movable into abutment with the end of the plate on said first mentioned saddle.

2. A machine for finishing stereotype plates including in combination a saddle, means for supporting a plate thereon in trimming position, an angularly traveling cutter at one end of said saddle for trimming an arcuate end of said plate, an auxiliary plate supporting saddle on the opposite side of said cutter, and means for supporting a plate on said auxiliary saddle in axially slidable relation to the auxiliary saddle for movement past the cutter and into matching abutment with the end of the plate on said first mentioned saddle.

3. A machine for finishing stereotype plates including in combination a saddle, means for supporting a plate thereon in trimming position, an angularly traveling cutter at one end of said saddle for trimming an arcuate end of said plate, means for moving said saddle toward and from said cutter, an auxiliary plate supporting saddle on the opposite side of said cutter, and means for supporting a plate on said auxiliary saddle in axially slidable relation to the auxiliary saddle for movement past the cutter and into matching abutment with the end of the plate on said first mentioned saddle.

4. A machine for finishing stereotype plates including in combination a saddle, means for supporting a plate thereon in trimming position, a cutter for trimming an arcuate end of said plate, means for supporting a trimmed plate adjacent the saddle in angular and axial alinement with said first plate, means for moving said plates relative to each other, one of said plates being slidably supported so that the trimmed ends of the plates may be brought into matching abutment.

5. A machine for finishing stereotype plates including in combination a plate supporting saddle, means for clamping a stereotype plate on said saddle, an angularly traveling cutter at one end of said saddle for trimming an arcuate end of said plate, an auxiliary plate supporting saddle on the opposite side of said cutter, means for supporting a plate on said auxiliary saddle in axially slidable relation to the auxiliary saddle for axial movement only past the cutter and into abutment with the end of a plate on said first mentioned saddle.

6. A machine for finishing stereotype plates including in combination a plate supporting saddle, an angularly travelling cutter at one end of said saddle for trimming an arcuate end of a plate on said saddle, an auxiliary saddle on the opposite side of said cutter, means on both saddle for angularly alining the plates supported thereon and including means for supporting a plate on said auxiliary saddle in axially slidable relation to the auxiliary saddle while maintaining said angular alinement for movement past the cutter and into abutment with the end of a plate on said first mentioned saddle.

7. A machine for finishing stereotype plates including in combination a plate supporting saddle, an angularly traveling cutter at one end of said saddle for trimming an arcuate end of a plate on said saddle, a stationary auxiliary saddle on the opposite side of said cutter, means on both saddles for angularly alining the plates supported thereon and including means for supporting a plate on said auxiliary saddle in axially slidable relation to the auxiliary saddle while maintaining said angular alinement for movement past the cutter and into abutment with the end of a plate on said first mentioned saddle.

8. A machine for finishing stereotype plates including in combination a plate supporting saddle, an angularly traveling cutter at one end of said saddle for trimming an arcuate end of said plate, an auxiliary plate supporting saddle on the opposite side of said cutter, a plate supported on said auxiliary saddle being axially slidable relatively to the auxiliary saddle past the cutter and into abutment with the end of a plate on said first mentioned saddle, a guard movable to protect the cutter and means for preventing sliding of the plate on the auxiliary saddle when the guard is in cutter protecting position.

9. A machine for finishing stereotype plates including in combination a plate supporting saddle, an angularly traveling cutter at one end of said saddle for trimming an arcuate end of said plate, an auxiliary plate supporting saddle on the opposite side of said cutter, a plate supported on said auxiliary saddle being axially slidable relatively to the auxiliary saddle past the cutter and into abutment with the end of a plate on said first mentioned saddle, a guard positionable to protect the cutter and means for preventing closing of the guard when a plate on the auxiliary saddle extends past the cutter.

10. A machine for finishing stereotype plates including in combination a saddle, means for supporting a plate thereon in trimming position, an angularly traveling cutter at one end of said saddle for trimming an arcuate end of said plate, an auxiliary saddle on the opposite side of said cutter, means for supporting a plate on said auxiliary saddle in axially slidable relation to the auxiliary saddle for movement past the cutter and into matching abutment with the end of the plate on said first mentioned saddle, and motor means for driving said cutter.

11. A machine for finishing stereotype plates including in combination a saddle, means for supporting a plate thereon in trimming position, an angularly traveling cutter at one end of said saddle for trimming an arcuate end of said plate, an auxiliary saddle on the opposite side of said cutter, means for supporting a plate on said auxiliary saddle in axially slidable relation to the auxiliary saddle for movement past the cutter and into matching abutment with the end of the plate on said first mentioned saddle, motor means for driving said cutter and operator controlled means for selectively inching the cutter or driving same at full speed.

NILS OLSEN TEMTE.
